UNITED STATES PATENT OFFICE

162,231

TOY VEHICLE

Paul B. Saunders, Jr., Aurora, Ill.

Application February 15, 1950, Serial No. 7,943

Term of patent 3½ years

(Cl. D34—15)

To all whom it may concern:

Be it known that I, Paul B. Saunders, Jr., a citizen of the United States and a resident of the city of Aurora, in the county of Kane and State of Illinois, have invented a new, original, and ornamental Design for a Toy Vehicle, of which the following is a specification, reference being had to the accompanying drawing, forming part hereof.

Figure 1 is a top plan view of a toy vehicle, showing my new design;

Figure 2 is a side view thereof as seen from the right, only one side being shown, as both sides are alike;

Figure 3 is a rear end view of the vehicle; and, Figure 4 is a front end view thereof.

I claim:

The ornamental design for a toy vehicle, as shown and described.

PAUL B. SAUNDERS, JR.
